UNITED STATES PATENT OFFICE.

ALFRED SCHICKERLING, OF MOUNT VERNON, NEW YORK.

ELECTRIC LAMP.

1,208,387.

Specification of Letters Patent. Patented Dec. 12, 1916.

Continuation of application Serial No. 110,022, filed July 19, 1916. This application filed August 11, 1916. Serial No. 114,377.

To all whom it may concern:

Be it known that I, ALFRED SCHICKERLING, a citizen of the United States, and a resident of Mount Vernon, in the county of West-
5 chester and State of New York, have invented certain new and useful Improvements in Electric Lamps, of which the following is a specification.

My improvements are applicable to elec-
10 tric lamps generally, and for various pur-
poses, although designed more particularly
for use in connection with the so-called
"head-lights" of automobiles, etc., the object
being to provide means whereby the larger
15 proportion of light rays projected from the
electric light bulb are concentrated and de-
flected to and by the usual parabolic re-
flector in such manner as to be directed
downward onto the road bed in advance of
20 the vehicle, while the light disclosed directly
by the upper portion of the lamp, considered
as a whole, is dimmed and subordinated,
and preferably tinted to render it unobjec-
tionable and harmless,—the concentrated
25 rays of white light only being projected
along the surface of the road. By this
means the dangerous and confusing glare
of the head light is obviated without de-
creasing, but rather by augmenting, the de-
30 gree of road illumination, and night traffic
is thus rendered more safe and agreeable, it
being well known that heretofore many acci-
dents have resulted from the blinding bri-
lliancy of unscreened or undimmed head
35 lights, especially where traffic is congested.

My invention consists primarily in the
use, in conjunction with the electric light
bulb and the ordinary parabolic reflector or
the equivalent thereof, of an inverted light-
40 transmitting hood piece of semi-transparent
or translucent material, preferably of amber
color, which modifies, tints, blends and dif-
fuses the light revealed by the upper portion
of the lamp, considered as a whole, while
45 hiding and completely concealing the elec-
tric bulb from sight when the lamp is
viewed directly from the front, the hood be-
ing open only at top to allow the rays from
the incandescent film to impinge directly
50 against the upper portion of the reflector
so as to project a beam of white light down-
ward in the ground in advance of the line
of travel, while the light visible above this
lower white beam of road light will be trans-
55 mitted and rendered harmless and agreeable

although sufficient in intensity to answer all
required purposes other than the direct illu-
mination of the road bed, it being under-
stood in this connection that my inverted
light transmuting hood is independent of 60
the electric bulb, forming no part thereof,
but rendering it invisible except possibly
as viewed at an acute angle at close range
looking down through the upper part of the
lamp and through the open top portion of 65
said hood; and furthermore that the hood,
in connection with its mount, entirely screens
the lower portion of the main or parabolic
reflector from the light emanating from said
electric light bulb except that passing 70
through the semi-transparent or translucent
material of which my light transmuting
hood is composed.

A secondary feature of my invention con-
sists in the combination and use in conjunc- 75
tion with my inverted open top light-trans-
muting hood of an inner supplementary re-
flector cup interposed between said hood
and the light bulb, which supplemental
reflector concentrates and deflects most of 80
the light rays emanating from the bottom
of the incandescent electric light bulb onto
the upper portion of the surface of the main
or parabolic reflector to be deflected and
projected thereby from the lower front por- 85
tion of the lamp together with the light rays
received by said upper portion of the main
reflector directly from the upper side of said
electric light bulb, thus further modifying 90
the light imparted to my light-transmuting
hood while intensifying the beam of white
road light projected downward from the
upper portion of said main reflector.

Incidentally my invention also includes 95
certain minor features in the construction
and arrangement of parts whereby my sup-
plementary deflector cup and diffusing hood
are adapted to lamps of forms and construc-
tions heretofore known and used, all as here-
inafter more fully set forth.

In the accompanying drawings, Figure 1, 105
is a front view of, say, an automobile lamp
designed to be used as a head light, and em-
bodying the essential features of my inven-
tion; Fig. 2, is a central vertical sectional
elevation of the same upon a larger scale 110
showing the invention as adapted to a lamp
reflector having a horizontal socket for the
electric light bulb, the front glass being omit-
ted; Fig. 3, is a front view, full size, of the

supplementary reflector cup and bracket shown in Figs. 1, and 2; Fig. 4, is a rear view of the same; Fig. 5, is a view of the under side of the bracket member shown in Figs. 3, 5 and 4; Fig. 6, is a side elevation of the electric light bulb socket and supplementary reflector cup; Fig. 7, is a front view of the dimmer or diffusing shade; Fig. 8, is a view of the upper side thereof; Fig. 9, a side elevation thereof; and Fig. 10, a rear elevation thereof.

In Figs. 1, and 2, I have shown only parts of a lamp or lantern sufficient to illustrate the practical embodiment of my invention in 15 a head-light or lantern for automobiles and the like, A, representing the customary concave mirror or reflector, usually of parabolic form, as related to the electric light bulb b,—said electric light bulb b, being positioned 20 at the focus of the parabola or substantially so.

The electric lamp b, is seated in the usual socket tube s, supported in the inlet sleeve a', of the reflector A, and rigidly secured in 25 position thereon by a set screw a², and nut a³, or equivalent mechanical expedient, said socket tube s, being formed with the bayonet slots s', s², for the reception respectively of radial studs b², on the bulb plug b', and 30 studs c', on the circuit plug c, to which the electric conductors are attached in the usual manner,—s³, representing the usual socket part, in which the yieldable contacts are mounted.

35 Secured to the inner end of the socket tube s, is a bracket member d, although it might be affixed rigidly to the back of the reflector or other stationary part if preferred. As shown in the drawings the bracket member 40 d, is formed with a split clamping ring d', adapted to encircle said inner end of the socket tube s, and having its opposed ends connected by a set screw d², as shown more particularly in Figs. 3, 4, and 5.

45 Attached rigidly to the main part of the bracket member d, is what I designate for convenience as the supplementary reflector cup r, adapted to cover the rear and lower portion of the electric light bulb b, and to 50 deflect the light rays received therefrom upward onto the upper forwardly inclined or parabolic surface a, of the main reflector A, to supplement the light rays impinging thereon directly from the upper side of said 55 electric light bulb and unite therewith to form an intensified beam of ground or road light which is projected downward and forward to and from the lower portion of the lamp, or in other words deflected downward 60 at an angle from and by the upper portion a, of the main reflector A. It will thus be understood that practically the full illuminative value of the incandescent film in the 65 electric light bulb b, is concentrated in the beam of road light projected from the lower

portion of the lamp or head light, so that it will most effectually reveal the line of advance without dazzling the eyes of those facing the head-light.

The supplementary reflector cup r, being 70 opaque of course cuts off a large percentage of light from the lower portion of the main reflector A, so that the light reflected upward from said lower portion of the main reflector will be slight and subdued as compared with the intensified beam of road light projected downward from and by the upper portion a, of the main reflector, as above set forth. To still further subdue and render unobjectionable the light projected 75 from the upper part of the main reflector and lamp, and at the same time render it agreeable and harmless to eyesight, I propose to use in conjunction with the electric light bulb b, and reflector A, either with or 80 without the supplementary reflector cup r, a dimming or diffusing glow-shade h, made of semi-transparent or translucent material, open at top for the passage of rays of light 85 direct from the electric light bulb b, to the upper surface a, of the main reflector A, but closed at front, bottom and sides. This hood h, for blending and rendering innocuous the light visible as emanating from the upper portion of the lamp is preferably of an 90 amber tint so as to absorb the ultra violet rays, but other colors may be used to neutralize certain rays, as preferred,—the object being primarily to attain, as it were, a 95 bifocal effect in that the light transmitted 100 visually by the upper portion of the lamp will be glow soft and non-actinic as compared with the intensified beam of white road light projected from the lower part of the lamp.

105 The front and side walls of my inverted light-transmuting hood or shade h, are of sufficient height to conceal the electric light bulb from direct front view, as will be understood by reference more particularly to Figs. 1, and 2. Even when said front and side walls are as low as shown in Fig. 2,—i. e., with their open edges in alignment with the top of the bulb b,—it will be seen that the latter could only be seen when in close proximity to the lamp, and then only by looking down through the extreme upper portion a, of the lamp, so that to all intents and purposes the incandescent light b, is 110 practically concealed and isolated from view, frontally considered, and hence no direct rays therefrom can possibly dazzle or annoy the eyes of observers under ordinary conditions,—the upper part a, of the main reflector A, overhanging and effectually concealing the open top of the hood h, unless viewed at an acute angle as hereinbefore intimated. It is to be noted in this connection that the opening in the upper side of 115 the translucent hood h, should be at least 120 125 130

commensurate in area with the size of the electric bulb b , to be used, so as to afford free and direct passage of light rays from the full area of the upper side of said light bulb; and that the upper portion a , of the main reflector A , overhangs the open top of the hood h , which is in fact housed and enclosed entirely within the confines of said main reflector, as clearly shown in Fig. 2, 10 of the drawings.

The modulating or glow shade h , may obviously be supported in position under the electric light bulb b , by various mechanical expedients. When used in conjunction with 15 the supplementary reflector cup r , as shown in the accompanying drawings, it may be supported on the same bracket therewith,—the hood h , being formed on its upper side with shoulders or heels h' , which fit in recesses d^1 , d^2 , (Fig. 5) formed in stirrups d^4 , d^5 , pendent from said bracket member d , which latter is also provided with a tightening screw d^5 , by which the shade h , may be secured in position. Similar results may 20 obviously be attained by the separate use of either the colored shade h , or the supplementary reflector r , but the best results are attained by the use of both acting in conjunction substantially as herein set forth.

30 I have herein shown adequate means for the support of both the supplementary reflector r , and shade h , with relation to the main reflector A , and the electric light bulb b , although I do not wish to confine myself 35 exclusively to the identical form and construction of parts described, since it is obvious that various modifications and mechanical expedients may be resorted to with like result, and without departing from the 40 spirit and intent of my invention in this respect.

What I claim as my invention and desire to secure by Letters Patent is,

1. In a lamp of the character designated, 45 the combination with the main reflector, and with an electric light bulb positioned therein, of an independently constructed inverted light-transmuting hood of translucent material closed at back and bottom and 50 formed with front and side walls which conceal the said bulb from frontal view, said hood being inclosed by and within the confines of the main reflector and being formed with an open top adapted to allow the light

rays from said bulb to impinge directly 55 upon the upper portion of said main reflector, for the purpose set forth.

2. In a lamp of the character designated, the combination with the main reflector, and with an electric light bulb positioned therein 60 of an independently constructed inverted light-transmuting hood of translucent material closed at back and bottom and formed with front and side walls which conceal the said bulb from frontal view, said 65 hood being inclosed by and within the confines of the main reflector and being formed with front and side walls the upper edges of which are as high as the top of said light bulb to conceal the latter from frontal view, 70 said hood being also formed with an open top commensurate in area with the size of the bulb and adapted to allow the light rays from said bulb to impinge directly upon the 75 upper portion of the main reflector, for the purpose described.

3. In a lamp of the character designated, the combination with the main reflector and with the electric light bulb positioned with relation thereto, of a supplementary 80 reflector cup covering the lower portion of said light bulb and a shade of translucent material partially inclosing said electric light bulb and said supplementary reflector cup, said shade being open above for the 85 passage of light rays directly from said bulb and from said supplementary reflector cup to the upper portion of the main reflector, for the purpose set forth.

4. In a lamp of the character designated, 90 the combination with a parabolic main reflector and with an electric light bulb positioned substantially in focal relation thereto, of a supplementary reflector cup covering the lower portion of said light bulb and a 95 shade of translucent material partly inclosing said electric light bulb and said supplementary reflector cup, said shade being open above for the passage of light rays directly from said bulb and from said supplementary 100 reflector cup to the upper portion of said parabolic reflector, for the purpose described.
